CHIP BREAKER

Application filed April 25, 1930. Serial No. 447,213.

This invention relates to chip breakers for woodworking machines and the object is to provide such a device which will be strong, work easily and not gather dirt in use.

- 5 Our invention will be well understood by reference to the following description of an illustrative embodiment thereof shown by way of example in the accompanying drawings, wherein:
- 10 Fig. 1 is a conventional longitudinal section through a part of a wood planing machine showing a section through the chip breaker bar;

Fig. 2 is a partial rear elevation, only some 15 of the shoes being shown; and

Fig. 3 is a section on the line 3—3 of Fig. 1.

Referring to the drawings, we have there shown a board *w* being advanced over the bed 5 of the machine by the feed rolls 7 for operation thereon of the upper cutter head 9 which turns counterclockwise as indicated by the arrow. Immediately to the rear of the cutter head 9 is located the chip breaker which herein comprises a bar 11 extending across the 20 machine, at the forward face of which are slidably mounted for up and down movement the individual shoes 13. Our invention more particularly relates to the construction of these shoes and the bar whereby the former 25 are carried by the latter, are free working, are strong and are unlikely to be jammed by dust and dirt entering therein.

Herein (see Fig. 2) the bar 13 is formed along its lower edge with the open-ended 30 slots 15 opening towards the bottom thereof and defining between them the substantial tooth-like projections 17. The lower portions of the shoes 13 are here shown as provided with suitable rearwardly projecting 35 ribs 19 adapted to be received in and work in the slots, being retained by the enlarged heads 21 which overlap the sides of the slots provided by the teeth 17, as clearly shown in Figs. 2 and 3. These parts are preferably one integral piece, the shoes 13 adjacent their lower

portions presenting an I section, as shown in Fig. 3, the web of the I working in a slot between portions 17. Preferably the shoes and the enlarged heads 21 fit together laterally and a slight clearance may be provided between the webs and the portions 17 as indicated by the shade lines in Fig. 3.

The upper ends of the shoes may be engaged with the bar 11 by means of the L-shaped gibs 23 bolted thereto and embracing the upper edge of the bar. Through these parts project the stems 25 secured to the upper edge of the bar and which carry the springs 27 against which the shoes work in the customary manner.

By the arrangement shown the shoes can be located and supported very close to the work, and as the work coming in contact therewith from the right, viewing Fig. 1, acts through a short lever arm exercising relatively little canting action, the shoes may move readily and in a vertical direction. There are no thin necks of metal likely to break, but on the contrary the section of the shoes at the bottom is of the most sturdy sort (see Fig. 3).

Since the shoes work in open-ended slots, or conversely since the parts 15 work in guideways in the shoes which extend uninterrupted therethrough to the bottom faces thereof, dirt and dust which may work in can drop out freely under gravity. We also prefer to slope the upper surface of the rib 19, as shown at 29, downwardly and rearwardly so that dirt will naturally fall therefrom instead of accumulating thereon, and the opposed wall 30 of the slot 15 at 31 may likewise be inclined. The upper edge of the bar embraced by the gib 23 may be reduced in thickness and joined to the main body of the bar by the rearwardly and downwardly sloping surface 33 from 35 which the dirt naturally works off in the reciprocating movement of the shoes.

It will be seen that in the arrangement shown except for the upper surface of the bar and without exception as far as the en-

gagement of the shoes at their lower ends, which are most exposed to the accumulation of dirt in the operation of the machine, the opposing surfaces all extend in such manner as to open freely to the exterior of the assembly and there are no horizontal surfaces or upwardly facing dihedral angles in which dirt might be pocketed and collect ultimately to interfere with the operation of the chip breaker.

We are aware that the invention may be embodied in other specific forms without departing from the spirit or essential attributes thereof, and we therefore desire the present embodiment to be considered in all respects as illustrative and not restrictive; reference being had to the appended claims rather than to the foregoing description to indicate the scope of the invention.

20 Claims:

1. In a chip breaker a bar having downwardly facing open-ended slots and shoes having projections on the rearward faces working in the slots and means cooperating with said projections to retain them in the slots.

2. In a chip breaker a bar having downwardly facing open-ended slots, shoes on the face of the bar having at the upper ends gibs embracing the upper edge thereof, ribs adjacent their lower ends working in the slots and enlarged heads on the ribs overlying the sides of the slots.

3. In a chip breaker a bar having downwardly facing open-ended slots and shoes having adjacent their lower ends portions of integral I section, the web of the I working in a slot.

4. In a chip breaker a bar having downwardly extending projections, shoes slideable on the bar having ribs working in the spaces between said projections, the upper faces of said ribs being sloped to discharge dirt therefrom, and means cooperating with the ribs to hold them engaged in said spaces.

5. In a chip breaker a bar having downwardly extending projections, shoes slideable on the bar having ribs working in the spaces between said projections, the upper faces of said ribs being sloped to discharge dirt therefrom, the opposed walls of said spaces being likewise inclined, and means cooperating with the ribs to hold them engaged in said spaces.

55 6. In a chip breaker a bar having along its lower edge a series of spaced projections and chip breaker shoes reciprocable thereon cut away to provide guideways to receive the projections, said guideways being open at both ends.

7. In a chip breaker a bar having a reduced upper edge portion connected with the body of the bar by a downwardly and rearwardly sloping surface, shoes on the front of the bar slidably engaged therewith at their lower

ends and having at their upper end gibs embracing said upper edge portion.

8. In a chip breaker, in combination, a bar and shoes slideable up and down thereon having means interengaging them with the lower portion of the bar providing opposing surfaces, all of which open freely to the exterior and without defining upwardly facing dihedral angles therebetween.

In testimony whereof, we have signed our names to this specification.

LAURENCE E. BLOOD.
PERCY H. YOUNG.
